GAUGING AND CONTROLLING MECHANISM

John R. Guenther, Appleton, Wis.

Application May 16, 1941, Serial No. 393,854

10 Claims.

(Cl. 200—52)

This invention relates to gauging mechanism and especially where combined with mechanism for control of supplemental devices to be controlled or operated in accordance with variations of the parts or material to be gauged.

A purpose of the invention is to provide improved gauging mechanism, and especially for application to continuous process machines as, for example, to a machine for slitting and cutting sheets from continuously moving paper webs, the gauging mechanism being adapted to respond to imperfections of the gauged material. In the machine mentioned, for example, the imperfections might be over- or under-thickness of the web caused by splices or tears, etc.

A further purpose is to provide gauging mechanism in an improved form adapted to control operation of other mechanism according to variations in the gauged material. Thus, in the slitting and cutting machine mentioned it is intended that the gauging mechanism shall operate indicating mechanism to visibly indicate when the paper web is normal or of an over- or under-thickness.

A further purpose is to provide an improved combination of gauging and other mechanism including an operative interconnection therebetween.

A further purpose is generally to simplify and improve the construction and operation of gauging devices, particularly for continuous gauging, and the construction, operation and relationship thereto of other devices controlled by the gauging devices, particularly devices for visibly indicating the condition of the gauged material as determined by the gauging devices.

The invention includes the construction and combination of parts as herein illustrated, described and claimed, but it is to be understood that various modifications are contemplated and that the invention includes such modifications of the structure illustrated and described as are within the scope of the claims.

The same reference characters have been used for the same parts throughout, and in the drawings:

Figure 1 is a semi-diagrammatic perspective view showing a paper slitting and cutting machine including gauging, controlling and indicating mechanism incorporating the invention.

Figure 2 is a diagram showing the interconnection of certain gauging means and indicating means shown in Fig. 1.

Figures 3A, 3B, 3C collectively show the construction of one of the gauging and controlling

units shown in Fig. 1, the views being enlarged; Fig. 3A being a vertical section taken approximately at line 3A—3A of Fig. 3C; Fig. 3B being a partial vertical section along line 3B—3B of Fig. 3A; Fig. 3C being a bottom view, partly in horizontal section, of the structure of Fig. 3A.

The paper slitting and cutting machine of Fig. 1 includes a plurality of rolls such as 10 each adapted to receive a plurality of paper webs such as 10a, 10a from rolls of paper, not shown, whereby to guide a desired number of paper webs to form a multiple thickness web 11, the web 11 being continuously pulled forward over a support 12 by pull rolls 13, and slit and edge-trimmed by spaced rotary cutters such as 14, and cut into sheet lengths by rotary knives at 15, the resulting sheets being traversed forward by a belt device 16 onto a receiving platform at 17, the platform being automatically lowered, by mechanism not shown, to receive successive sheets at substantially the same level.

Two similar gauging and control units 18, 18 are rigidly supported from the frame of the machine of Fig. 1, as by cross support members 18a, 18a, Figs. 3A, 3C, not shown in Fig. 1, the units being respectively adjacent opposite lateral edges of the traveling web 11.

The units 18, 18 are of corresponding construction and therefore only one unit need here be described in detail. Referring to Figs. 3A, B, C the units each include a housing having a hollow main portion 19a rigidly fixed with the cross frame members 18a, 18a by any suitable means, not shown, and having a cover 19b removably fixed on the main portion. Within the gauge housing are two similar switch units such as 20, 20 respectively fixed on different carriers such as 21, 21. Each of the carriers 21 has an end portion such as 21a rigidly fixed with the inner wall of the housing by suitable means, not shown, a resilient or spring portion such as 21b, and a channel portion such as 21c.

The channel portion of each carrier 21, together with the associated switch unit 20, is continuously yieldably urged upwardly in Fig. 3A, as by suitable springs such as 22, but adjustable stop means is provided including micrometer adjusting screws such as 23. It will be understood that there are two adjusting screws such as 23 for each of the gauge units 18, the screws being respectively operable to adjust the different switch units 20, the screws being threaded in nut sleeves such as 24 rigidly fixed with the housing cover 19b, and the inner ends of each screw bearing against the corresponding carrier

channel portion 21c, the abutment end of the screw being rotatable in a clearance slot provided in a member such as 25 fixed on the channel portion 21c. The engaged slots prevent lateral displacement of the carriers 21 and switch units 20 during the rotation of the adjusting screws.

Fixed on the upper end, Fig. 3A, of each of the screws 23 there is an exterior sleeve such as 26 which rotates and moves axially with the screw, whereby the two parts 24, 26 are provided with cooperating indicating graduations, not shown, in the manner well known for micrometer devices etc., such graduations serving to visibly indicate the particular adjustment of the switch units 20 controlled by the screw, and for individually varying the adjustment of the switch devices by predetermined amounts in either direction.

Each of the switch units 20 is similar in construction and it will therefore only be necessary to describe one unit in detail. The switch units include a hollow housing such as 20a rigidly fixed with the carrier portions 21c by any suitable means, not shown. Within the housings 20a there is a resilient or yieldable switch arm such as 27 which is rigidly fixed with the housing at the one end and at the other or yieldable end carries upper and lower contact portions respectively engageable with an upper contact such as 28 and with a lower contact such as 29. The switch arm 27 is normally biased, as by its own resiliency or by suitable springs, not shown, for the arm to effect a closed circuit with the lower switch contact 29. The housing 20a provides a suitable guide or slide for an axially shiftable plunger such as 30, the inner end of the plunger being continuously urged to contact the switch arm 27 by the means of a light spring such as 31, the other end of the plunger extending outside the housing, as shown, where it may directly contact with an article or material to be gauged, as shown in Fig. 2, or may be provided with a contactor button such as 30a, Fig. 3A, for effecting a larger area contact surface. Each of the gauge units 18 is provided, in this instance, with a guide or shield member, such as 32 fixed on one of the frame members 18a at the side toward the incoming multiple web 11, whereby to guide the web underneath the end of the gauge plunger 30.

The two gauge units 18, Fig. 1, together provide four independently adjustable gauge devices each having an independent adjustment screw 23 and each having an associated switch device 20 which may be independently controlled for operation in accordance with the adjustment of the corresponding adjusting screw. Thus when the plunger 30 is contacting the gauged material the screws 23 may be adjusted for the switch arm 27 to effect a closed circuit with the upper contact 28, or with the lower contact 29, or to be in intermediate position interrupting both said contacts, and any of these several adjustment positions may correspond with the standard or normal thickness of the part to be gauged, or with a predetermined amount of over- or undersize thereof.

Such switch contact variations may be utilized in various ways for controlling various supplemental devices. In the present instance the supplemental devices visibly indicate, to the operator of the machine of Fig. 1, any defects in the multiple paper web 11 such, for example, as a tear-out or a doubled thickness in one of the component paper webs 10a which form the multiple web 11. For such result the two switch devices such as 20 of each gauging unit 18, 18, Fig. 1,

respectively control different lights in two groups of lights such as 35, 35, Fig. 1, the different light groups respectively corresponding to the different gauge units. In the present instance, for each group of indicator lights, one of the light bulbs is lighted when the multi-web 11 is over-thick at the point of gauging, as where a component web 10a is doubled or overlapped, while the other light lights up when the multi-web is under-thick, as where there is a tear-out in a component web, or where one of the normal number of component webs is missing. If no lights are lighted the multi-web is normal. Preferably, differently colored lights are used as, for example, a red in each group to indicate over-thickness and a green light to indicate under-thickness.

The operating interconnection of the gauging and indicating devices is the same for each of the gauge units 18, 18, Fig. 1, and will therefore be described in detail for only one such unit. Referring to Fig. 2, 35r is a red light used in one of the indicator sets 35, 35 to indicate oversize when lighted, and 35g is a green light used in the same set to indicate undersize.

For control of the light 35r the connections are such that undersize of the web 11 operates to close a circuit through the light from a current supply line 36 and through the corresponding switch unit 20, the current operating through the switch arm 27 and the lower contact 29 whenever the multi-web 11 is a predetermined amount under size at the point where the plunger 30 presses against the web. To effect an adjustment for such result the adjusting screw 23 of the switch unit 20 controlling the light 35r is backed up until the normally closed contact 29 is closed while a web 11 of normal thickness is on the support 12. The screw 23 is then set forward until the light 35r is extinguished, and then a slightly further distance forward, less than the thickness of one of the component webs 10a. With such adjustment the light 35r will remain unlighted so long as the multi-web 11 is not undersize by an amount as large as the thickness of one of the component webs, but will be lighted whenever the web is undersize by as much as one component sheet thickness, or more.

The light 35g is lighted whenever the multi-web 11 is over-thick by as much as one component sheet thickness, the gauge and indicator connections being as follows:

One side of the current supply line 36 is connected to the flexible arm 27 of the switch 20 which controls the light 35g. The other side of the supply line is connected to the normally closed contact 29 of the switch through a heating resistance 40a of a control unit generally denoted as 40, and through a contact 40b associated with a pivoted armature arm 40c which is continuously urged by a spring 40d toward the position closing the contact. The heating resistance 40a is wound on, but insulated from, a flexible bi-metal arm 40e which when heated bends to close a contact with an adjustable contact screw 40f, thereby completing a circuit from line 36 through the switch contact 29, if that contact is closed, and through the bi-metal arm 40e, the screw 40f, and a magnet coil 40g associated with the pivoted arm 40c, whereby the contact 40b is opened and at the same time another contact 40h is closed, the resulting circuit through contact 40h and the magnet coil 40g operating as a holding circuit to maintain contact 40b open and contact 40h closed until such time as the switch plunger 30

is moved upwardly in Fig. 2 to open the contact 29.

Another pivoted contact arm 40i is connected for movement with, but insulated from, the arm 40c. When arm 40c is in the position closing the contact 40b, that is to say whenever the circuit through magnet 40g is opened, there is a closed circuit from line 36 through the light bulb 35g and through the pivoted arm 40i and a contact 40j associated therewith, but whenever the magnet 40g is energized, as described, the contact 40j is open and the light 35g is extinguished.

For effecting the result mentioned the adjusting screw 23 of the switch 20 associated with light 35g is adjusted downwardly until the position of plunger 30 when bearing on a multi-web 11 of normal thickness just fails to open the contact 29. With this adjustment there will be a brief period, while the resistance 40a is heating up, in which the light bulb 35g is lighted but, as soon as the bi-metal arm 40e is heated, the contact with screw 40f will be closed whereby to establish the initial circuit through contact 40b to energize magnet 40g and thereby open the light circuit contact 40i to extinguish the light, the magnet holding circuit through contact 40h subsequently operating as described to maintain the light extinguished until such time as the multi-web 11, at the point where it presses against plunger 30, is sufficiently over-thick to break the contact 29, as where one of the component sheets has been torn and folded back, or has been broken and spliced with an overlap. At such time the circuit through light bulb 35g is again completed through the contact 40j, whereby to indicate to the operator that the web 11 is too thick.

It will be noted that when the circuit of the light bulb 35g is closed as described, indicating an over-thickness of the web 11, the resistance 40a is cold, whereby it results that even if the over-thickness of the traveling web 11 is of very short duration the closed circuit for the indicator light will be maintained while the bi-metal arm 40e is being heated up to establish the initial magnet circuit through contact screw 40f. The screw 40f may be adjusted to provide a suitable interval of lighting of the bulb 35g even where the oversize defect of web 11 is of such short duration that contact 29 is closed substantially instantly after it is opened.

The lag in extinguishing bulb 35g, as just described, makes the initial adjustment of the corresponding switch 20 by its adjusting screw 23 a matter of some difficulty unless special means are provided therefor. For this reason there is provided, for purposes of such initial adjustment, a pilot light 42, Fig. 2, which is connected to receive current from line 36 upon closing of the normally open upper switch contact 28. This arrangement may be used for the initial adjustment of switch 20 for the described operation of the indicator light 35g, as follows: With the switch operating plunger 30 bearing on a web 11 of normal thickness, the adjusting screw 23 is set forward until the contact 28 is closed, thereby lighting the pilot light 42. The screw 23 is then adjusted in the other direction, upwardly in Fig. 2, until the pilot light is extinguished by the opening of the contact 28, and adjusted a further known distance, as determined by the adjusting screw, the further amount depending upon the known clearance between the contacts 28, 29.

What is claimed is:

1. In a device for contacting the surface of

work to gauge work thickness, the combination with a work support of a carrier disposed above the support and pivoted for movement to and from the work surface, a spring urging said carrier in one direction of movement, an adjusting screw constituting a stop adjustably determining the position of the carrier under the bias of said spring, a unitary switch device mounted on the carrier and comprising relatively movable switch contacts in operative association for circuit opening and closing movement, one of said contacts being mounted for movement to and from said support, and an actuator having a work engageable end depending below said carrier toward said support and having a contact engaged portion for directly transmitting movement from the work for contact actuation.

2. In a gauge for operating on the face of work to determine the thickness thereof, the combination with a work support, of a switch having a contact arm generally parallel to the work surface, a contact mounted on said arm for movement to and from the surface, and a fixed contact engaged by the arm-mounted contact for operative circuit closing, a reciprocable contact actuator engaging said arm and extending therefrom directly toward said surface, and a carrier upon which said switch is bodily movable to and from the surface of the work for positioning said actuator with respect thereto, and means for adjustably positioning said carrier.

3. The device of claim 2 in which the carrier is provided with a support and a pivotal connection with the support and has means biasing the carrier in one direction about said pivot, said positioning means comprising a screw opposing the movement of said carrier in response to said bias.

4. In a gauge, the combination with a work support and a gauge support, of a carrier disposed in spaced relation to the work support and having a flexible arm connecting it with the gauge support, a unitary switch structure mounted on the carrier and including relatively movable contacts and a contact actuator projecting from the carrier toward the work support in a position to be engaged by work on the work support, means biasing the carrier in one direction of movement respecting the work support upon said flexible arm, and a screw stop adjustable to determine the limit of movement of the carrier and the switch structure subject to said bias whereby to provide for the precision positioning of said actuator and switch structure respecting said support.

5. The device of claim 4 in which the switch structure includes a relatively fixed contact and a flexible contact arm extending in general parallelism with the face of the work support and provided with a movable contact normally closed upon the fixed contact.

6. The device of claim 4 in which the switch structure includes a relatively fixed contact and a flexible contact arm extending in general parallelism with the face of the work support and provided with a movable contact normally closed upon the fixed contact, and the contact actuator comprises a reciprocable rod extending approximately at right angles to the work support and said arm and provided with a supporting spring adequate to hold said rod in engagement with said arm but incapable of exerting sufficient bias to move said arm to open circuit position.

7. In a device for contacting the surface of

work for gauging the thickness thereof, the combination of a unitary switch device comprising a unitarily movable support, a contact fixed on said support, a movable contact engageable with the fixed contact, a flexible carrier lever to which the movable contact is mounted, the end of said lever remote from said movable contact being fixed to said support, a feeler member engaging an intermediate portion of the flexible carrier lever and extending approximately at right angles thereto for engagement with the work, and means for the critical adjustment of said support respecting the work.

8. The device of claim 7 in which said means comprises a flexible element upon which said support is mounted, a spring biasing said element for movement in one direction respecting the work, and a screw engaging said support in opposition to said bias for adjusting said support in the opposite direction respecting the work.

9. In a device for gauging the thickness of a piece of work, the combination of a unitary switch device comprising a support, a contact carrying lever mounted on said support and provided at its free end with a contact, relatively fixed means between which said contact has lim-

ited movement on the free end of the lever, at least one of said means comprising a complementary contact, a feeler engaging an intermediate portion of said lever and extending thence approximately at right angles toward the surface of work to be gauged, said lever having a general direction approximately paralleling such surface, and means for the precise bodily adjustment of said support to and from said surface, such means being the sole accessible means for determining the relation between the relatively movable and fixed contacts of said switch.

10. The device of claim 9 in which the means for adjusting the support comprises a case in which said support and switch are wholly enclosed, a flexible member mounted within the case and carrying said support, a spring biasing said support for movement in one direction respecting the surface of the work, and a screw projecting through said case and engaging said support in opposition to said spring for moving it in the opposite direction respecting the work surface.
